DUNCAN W. PECK, OF SYRACUSE, NEW YORK.

SPARK-PLUG.

1,166,385.

Specification of Letters Patent. Patented Dec. 28, 1915.

Application filed January 10, 1912. Serial No. 670,411.

To all whom it may concern:

Be it known that I, DUNCAN W. PECK, of Syracuse, in the county of Onondaga and State of New York, have invented a certain 5 new and useful Spark-Plug, of which the following is a specification.

This invention has for its object the production of a particularly simple and efficient spark plug, and it consists in the combinations and constructions hereinafter set forth and claimed.

In describing this invention reference is had to the accompanying drawing in which like characters designate corresponding 15 parts in all the views.

Figure 1 is a longitudinal sectional view of one form of this spark plug. Fig. 2 is a sectional view on line "A—A", Fig. 1. Figs. 3, 4 and 5 are sectional views of other forms 20 of my spark plug.

1 is the body of the spark plug, the body being provided with external threads 2 for turning into a threaded opening of the cylinder of an engine. Said body 1 is formed 25 with a lengthwise axial passage 3 having its outer or upper end closed by a bushing 4 threading thereinto, the bushing terminating short of the inner end of the body forming a recess. This bushing is formed with 30 an axial opening decreasing in diameter toward its outer or upper end. The bushing 4 is provided with a flange 5 opposed to the upper face of the body 1, and an annular packing 6 is interposed between said flange 35 5 and the upper face of the body 1.

The central electrode or terminal of the spark plug extends axially through the bushing 4 and comprises outer and inner sections 7 and 8 arranged end to end, the 40 outer section 7 being formed with a lengthwise passage 9 opening through the inner end face thereof, said passage usually extending axially of the section 7 the full length thereof. The section 7 is also formed 45 with a plurality of transverse slots 10 opening through its inner end face and also into the passage 9, the slots 10 being usually arranged in transverse radial alignment, and two of the slots opening through diametri- 50 cally opposite points of the periphery of the section 7 and the other two slots extending at a right angle to the first-mentioned slots and opening through the periphery of the section 7. These slots are usually formed

by sawing the inner end of the section 7 55 along diameters arranged at a right angle to each other. The forming of such transverse slots or passages, as set forth, is much more economical than boring passages communicating with the central passage. 60

One end of the section 8 is forced into the bottom of the passage intersected by the slots 10 and terminates short of the bottoms 11 of the slots so that the fluid inserted through the passage 9 will have an outlet 65 through the transverse slots or passages into the recess 3. The fluid forced through said passage 9 clears the passage and the terminals of the plug of any soot deposited and flows to the end of the section 8 to insure 70 ignition within the cylinder by a spark between the lower end of the section 8 and the other electrode 12 which projects from the inner end of the body and across the recess 3. The slots 10 in effect form prongs at the 75 inner end of the section 7; and the inner section 8 extends between these prongs and is held in position thereby with its contiguous end face spaced apart from the horizontal plane of the bases of the prongs and of 80 the bottoms of the slots. The slots constitute the spaces between the prongs and the lengthwise passage 9 opens into said spaces at the intersection thereof.

13 is a sleeve of insulation decreasing in 85 diameter toward its outer or upper end and fitting the axial opening of the bushing 4, said sleeve encircling the section 7 of the central electrode and projecting beyond the inner end of the same forming an annular 90 chamber 14 around the inner or upper end of the section 8 against the walls of which impinges the fluid projected from the slots 10.

Preferably my spark plug is so formed 95 that no chamber or socket in which soot can accumulate, intervenes between the periphery of the lower end of the sleeve 13 and the inner face of the body 1 and usually the bushing 4 is formed with an integral exten- 100 sion 15. However, as seen in Figs. 3, 4 and 5 the annular space between the periphery of the lower end of the sleeve of insulation 13 and the inner face of the body 1 may be filled by an additional sleeve of insulation 16 forming an extension of the bushing, the lower end edge of the sleeve 16 being flush with the lower edge of the sleeve 13. As

seen in Fig. 3 said sleeve 16 may be held in position by an annular shoulder provided on the inner face of the socket 3 and such shoulder may consist of a ring 17, Fig. 3, sprung into an annular groove 18 provided in the walls of the recess 3, or as seen in Fig. 4 may be a projecting annular shoulder 19 formed integral with the walls of the socket 3, or as seen in Fig. 5 said shoulder 19 may be in the form of a ledge 20 facing upwardly and provided by forming the lower portion of the recess 13 of less diameter than the portion in which the bushing 4 is arranged.

15 21 is a sleeve or block of insulation having an axial opening decreasing in diameter toward its upper end and fitting the portion of the sleeve 13 above the bushing 4. The lower end of the sleeve 21 is mounted on the 20 upper face of the bushing 4 and the upper end of said sleeve 21 forms a seat for the nut like base 22 of a cup 23 screwing on the reduced upper or outer end 24 of the section 7 of the central electrode. The body 25 of the cup is formed spherical for receiving that type of wire terminals or binding devices designed to grasp or fit spherical binding posts. Other forms of terminals as the forked type may be attached to the plug by 30 clamping the same between the base 22 of said cup and the opposing surfaces of the contiguous parts of the spark plug.

25 25 is a plug screwing into the cup 23 and serving as a closure therefor, and for the 35 passage 9 of the section 7 of the central electrode, the plug being formed with a conical inner end 26 which seats near its point against a beveled seat 27 at the upper end of the passage 9, the remaining area of 40 the conical end 26 being spaced apart from the rounding bottom 28 of the cup 23. The plug 25 is formed with an inclined passage 29 therefor, the lower end of which is out 45 of alinement with the passage 9 and opens through a portion of the conical surface spaced apart from the bottom 28 of the cup 23.

A spark plug constructed as described is particularly advantageous in that the sections 50 of the central electrode can be cheaply assembled and the transverse passages or slots of the upper section can be quickly and cheaply formed therein.

What I claim is:

55 1. A spark plug comprising a central electrode including inner and outer sections arranged end to end, the outer section being formed with a lengthwise passage and with prongs at its inner end, the passage opening 60 into the spaces between the prongs, and the inner section having one end thereof extended between the prongs and frictionally held in position thereby with its contiguous end face spaced apart from the horizontal plane 65 of the bottoms of the spaces between the

prongs, whereby lateral passages are provided from the lengthwise passage, substantially as and for the purpose specified.

2. A spark plug comprising a central electrode including inner and outer sections arranged end to end, the outer section being formed with a lengthwise passage and with prongs at its inner end, the spaces between the prongs intersecting, and the inner end of the lengthwise passage opening into the 70 intersection of the spaces, and the inner section of the electrode having one end extending between the prongs at the intersection of the spaces between the same, substantially as and for the purpose set forth.

3. A spark plug comprising a central electrode including inner and outer sections arranged end to end, the outer section being formed with a lengthwise axial passage and with a plurality of prongs at its inner end, 80 the prongs being arranged so that the spaces between the same extend substantially diametrically of the inner end of said outer section, said axial passage opening into said spaces, and the inner section of the electrode 90 having one end extending between the prongs in alinement with the passage, substantially as and for the purpose described.

4. A spark plug comprising a central electrode including inner and outer sections arranged end to end, the outer section being formed with a lengthwise passage, and with a plurality of prongs at its inner end arranged so that the spaces between the prongs extend diametrically of the inner end of the 100 outer section and intersect at the horizontal axis thereof, said lengthwise passage opening into the spaces between the prongs at the intersection thereof, and the inner section having one end extended between the 105 prongs at the intersection of the spaces between the same, substantially as and for the purpose specified.

5. A spark plug comprising a body formed with an axial passage, a bushing arranged 110 in the passage and terminating short of the end of the body forming a recess, a sleeve of insulation extending axially of the bushing, the bushing having an extension for encircling the lower end of the sleeve of insulation and filling the space between the periphery of the lower end of such sleeve and the inner face of the passage of the body, and a central electrode arranged within the sleeve of insulation, substantially as and for 115 the purpose set forth.

6. A spark plug comprising a body formed with an axial passage, a bushing formed with an axial passage arranged in the upper portion of the body and terminating short 125 of the lower end of the body forming a recess, a sleeve of insulation arranged in the axial passage of the bushing and the bushing being provided with an integral extension, the end face of which is flush with the 130

edge face of the sleeve of insulation, and a central terminal within the sleeve of insulation, substantially as and for the purpose described.

5 In testimony whereof, I have hereunto signed my name in the presence of two attesting witnesses, at Syracuse, in the county

of Onondaga, in the State of New York, this 7th day of Dec., 1911.

DUNCAN W. PECK.
